UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 20,354, dated December 2, 1890.

Application filed May 12, 1890. Serial No. 351,563. Term of patent 14 years.

To all whom it may concern:

Be it known that I, EDWARD WESTON, of Newark, Essex county, New Jersey, have invented and produced a new and original 5 Design for Cases for Electrical Measuring-Instruments, of which the following is a specification.

My design is intended for application to the inclosing-cases of electrical measuring-instruments; and it consists in the configuration of 10 said case, as hereinafter specified.

In the accompanying drawing a front view of said case is represented.

The general outline of my design is that of 15 a circle surmounted by a large sector and disposed above a base.

In the drawing, above the circular portion

A, appears the sector B. Around the edges of the sector B appears a frame or raised border having the sides C D in the form of circular arcs and the sides E F straight. Below the circle A appears a portion G, the lower edge H of which is straight. In other respects the conformation of said portion G is not material.

I claim—

The design for an electrical-instrument case, substantially as herein shown and described.

EDWARD WESTON.
